UNITED STATES PATENT OFFICE.

ALBERT A. ABRAMS, OF ST. LOUIS, MISSOURI.

SHIRT.

SPECIFICATION forming part of Letters Patent No. 640,731, dated January 9, 1900.

Application filed September 11, 1899. Serial No. 730,101. (No model.)

To all whom it may concern:

Be it known that I, ALBERT A. ABRAMS, a citizen of the United States, residing at St. Louis, State of Missouri, have invented certain new and useful Improvements in Shirts, of which the following is a full, clear, and exact description, reference being had to the accompanying drawings, forming a part hereof.

My invention has relation to improvements in shirts; and it consists in the novel construction of shirt more fully set forth in the specification and pointed out in the claims.

In the drawings, Figure 1 is a front view of a shirt having my improved attachment. Fig. 2 is a rear view showing the elastic band and guiding-loop therefor. Fig. 3 is an enlarged detail front view of the attachment or bosom extension. Fig. 4 is a section on line 44 of Fig. 3. Fig. 5 is a front view of a modified form of attachment, dispensing with the use of the elastic band. Fig. 6 is a view similar to Fig. 5, showing the application to the shirt when donned by the wearer; and Fig. 7 is a section on line 77 of Fig. 5.

The object of my invention is to provide the bosom of an ordinary shirt with a wing or lateral extension which can be retained in close contact with the body of the wearer, thereby preventing the bulging of the shirt-bosom, as is now generally the case, especially with stiff bosoms.

A further object is to provide an extension the pull or tension on which shall distribute the strain on the bosom uniformly throughout the length of the latter.

In detail the invention may be described as follows:

Referring to the drawings, 1 represents the body of the shirt, and 2 the bosom thereof. Projecting laterally from each edge of the bosom, but free from the body of the shirt, are wings or extensions 2', each provided with a lower short arm 3 and an upper long arm 3'. The outer edges of the arms 3 3' incline outwardly, the same terminating at the base of a neck or coupling-arm 5, which terminates in a head 6, projecting beyond the sides of the neck to an extent determined by the shoulders or offsets 7. The coupling-neck is provided at a point approximately in line with the shoulders 7 with a slit 8, adapted to receive the terminal clasps or hooks 9 of the elastic band 10, passed around the shirt, and adjusted at will by means of a slide 11, as is obvious. To insure the band remaining in place and prevent the same from sagging or working upward, I provide the back of the shirt with a guide-loop 12, through which the band is passed. As seen from the foregoing, the extensions 2', (including the arms 3 3'), with their necks 5 and heads 6, are each cut from a single piece of material, each extension being so secured to the bosom as to bring the line of tension or draft upon the extensions or, in other words, the point of connection between the hooks 9 and the extensions in a line passing approximately directly under the armholes, as best seen in Figs. 1 and 2, where by reason of said disposition of the extensions the band 10 is caused to pass around the body of the wearer directly below the armholes of the shirt. This is not only the most convenient location for the point of coupling between the extension 2' and the elastic band, but by making the arms 3 3' of each extension of unequal length and by disposing the longer arm above the shorter the strain upon the bosom is distributed to the best advantage. Again, the neck 5 having a certain width, the draw or pull upon the extension is not confined to a single point, (as where the connection is made by a buttonhole and button formed, respectively, on the band and extension,) but the pull or tension is along lines parallel to the sides of the neck 5. To better take up this strain, I provide each neck with a rear reinforcing-strip 13, the base of which is secured to the rear of each extension, the free slotted end of the said strip being passed over and embracing the neck along the front side of the extension, (see Fig. 3,) the shoulders 7 preventing the neck of the extension from passing out of the slit of the strip. When the extension is under tension, the outer wall of the slit of the strip 13 bears against the base of the neck 5, the strain being partially taken up by the strip under the circumstances. Should the reinforcing-strips be sewed, however, along the front of the extension, as shown by 13' in Figs. 5, 6, and 7, in which case the free edge adjacent to the slit end of the strip becomes disposed on the rear face of the neck 5, the band 10 may be omitted and the extension 2'

held down and the bosom thus prevented from bulging by passing the suspender 14 between the extension and strips 13'. The strip 13', therefore, when sewed on the front of the extension serves as a guide for the suspender for the purpose referred to, and though the omission of the band 10 under the circumstances is preferable it is not necessary.

To retain the bosom against working up, I provide the base of the same with a sectional or partitioned tab or loop 15, through either opening of which the button of the drawers can be passed.

It is to be understood that I do not limit the present invention to any particular character of either bosom or shirt, and it is further obvious that the device may be altered in many details without departing from the spirit of my invention. Thus while the extensions are herein described as separate pieces sewed to the bosom they may, in fact, be integral extensions thereof. So, also, can the hooks be made of wire or of any shape or design so long as they remain permanently in place after having once been inserted through the slits of the necks 5.

Having described my invention, what I claim is—

1. In a shirt, a bosom, lateral extensions

therefor, each extension comprising two arms 30 of unequal length, the longer arm being disposed above the shorter, a coupling-neck at the meeting bases of the two arms, an expanded head for the neck, a slit formed in the neck, an elastic band adapted to have its 35 free ends coupled to the slotted ends of the necks, and a guide-loop at the back of the shirt for guiding the band, substantially as set forth.

2. In a shirt, a bosom, lateral extensions 40 therefor, each extension comprising two arms of unequal length, a coupling-neck at the meeting bases of the two arms, a head at the free end of the neck, offsets or shoulders formed between the head and neck, a reinforcing-strip secured at its base to the extension, and having its free end slit to receive the head and neck of the extension, and means 45 for coupling the necks of the extensions to the free ends of a suitable band adapted to pass 50 around the body of the wearer, substantially as set forth.

In testimony whereof I affix my signature in presence of two witnesses.

ALBERT A. ABRAMS.
